DABBING BRUSH FOR WOOL COMBING MACHINES

Thomas Lorimer, Bradford, England

Application January 11, 1940, Serial No. 313,383
In Great Britain July 17, 1939

3 Claims. (Cl. 19—124)

This invention relates to improvements in dabbing brushes used in wool combing operations, and refers to brushes of the kind employing a plurality of sections adapted to be reversible endwise, and more particularly to that type of brush having a back portion which may be permanently attached to the dabbing mechanism, said back portion being provided with depending lugs to receive securing bolts adapted to pass horizontally through adjacent and abutting sections.

In the improvement under consideration there is no necessity for more than three brush sections, one to cover that part which is subject to most wear, another to abut as it were parallel with the first section and pass beyond same, and a third section to abut with the other two sections. The first and second mentioned sections are not connected by bolts, but the second and third sections are connected, preferably by one bolt, which passes through the stocks and is secured between depending lugs. The first mentioned section is slid into position between the second section and a depending lug on the back, and pressure is applied to press the section together such as by an interposed leaf spring carried by one of the depending lugs and capable of being pressed towards a section by an adjusting or clamping screw.

The sections are rectangular in form and are endwise reversible in convenient manner and when fitted together form the brush face. It is the first mentioned section that is subject to most wear and it will be preferable to stock a larger number of these sections than of the other two. The present arrangement and construction is such that on the release of the adjusting or clamping screw pressure is released and the worn section may be readily pulled out of place to permit it to be reversed, or a new one to be slid into position and be secured by the tightening up of the adjusting screw, a very easy and rapid operation which can be performed without taking the brush from the dabber foot. Further it will be understood that the depending lugs may provide for expansion or shrinkage of the brush stocks which may occur from storage effects, the interposed leaf spring giving this advantageous effect. The face area of the back portion will preferably be rather greater than of the area covered by the assembled sections.

In some forms the depending lugs may have lips adapted to take over the under edges of the stocks of the sections to ensure that the stocks are pressed towards the back, but a really tight fit from such construction is not essential.

I may deviate from the above description in minor detail without impairing the efficiency of the apparatus.

In describing my invention in detail reference is made to the accompanying sheet of drawing, similar letters indicating similar parts, in which:

Fig. 1 represents an under face view of a dabbing brush according to my improvement.

Fig. 2 represents an end view of the brush and back, in acting position.

Fig. 3 represents a section of the brush and back on line *a*—*b* of Fig. 1.

Fig. 4 represents a plan view showing a modified form of securing two sections by one bolt.

Fig. 5 represents an elevation of depending lug and pressure applying means, referred to.

To carry my improvements into effect I provide a main back member *D* conveniently adapted to be secured to what is known as a dabber foot. 20 As means for securing the back *D* to a dabber foot may vary, such means are not illustrated. The said back member, of suitable material, such as a metal, fibre, or wood, metal being preferred, is given a somewhat L shaped form to correspond to the shape of the brush which is assembled from a plurality of reversible sections and secured to the back *D* in manner hereinafter described.

I am aware that a back member and reversible sections as before mentioned have previously been proposed and to secure such sections to the back, the said back has carried depending lugs between which the sections have been placed and secured by bolts passing through such lugs and all the sections. 35 This construction is known by my previous British specification 485,218.

In the form of brush under consideration the brush sections are denoted by the letters *A*, *B* and *C*, *A* being a section to cover that part of the brush which is subject to most wear, *B* being a section abutting against *A* but of greater length, and *C* being a section substantially square to fill in the angle formed between *A* and *B* and give a usual configuration to the brush. Three sections are usually sufficient for all practical purposes.

The brush back *D* has an under face area slightly larger than the area of the assembled stocks of the sections, and is provided with depending lugs *L*, *L*¹, and *L*², *L* being on one side 50 and *L*¹ and *L*² on the opposite side. Whilst these lugs may be integral with the back, they are preferably secured to the back by bolts, screws, rivets, or the like *L*^x.

All the sections are rectangular and are reversible endwise. The stocks of the sections *B*

and C are drilled through as at B¹ and C¹ and a bolt E is utilised to secure such two sections between the lugs L and L¹. In Fig. 1, the bolt E is not in a mid position with regard to the section C and such section is provided with two drilled holes C¹ as shown. In Fig. 4, the bolt E is arranged to pass through the centre of the section C and only one drilled hole C¹ is required. The section B will have two drilled holes B¹ as shown in Fig. 1.

The section A is undrilled in its stock and is secured in the following manner.

The brush back D is of slightly larger area than the assembled sections and this leaves a space D¹ between the side of the back and the edge of the stock of the section B and thus provides a certain amount of play for the section A and part of the section B between the lugs L and L¹. Consequently the section A may be easily slid into and out of position, as indicated by the arrow thereon. The lug L¹ is by preference provided with a lip or flange L³ adapted to act as a slide guide for the section A and to slightly overlap the edge of its stock.

In order to secure the section A, means for applying pressure against either the section B or the section A to clamp the sections between the lugs L and L¹ are provided.

The most convenient form is by means of a leaf spring S attached to the lug L at a point as S¹ towards the bolt E, (see Fig. 5) and with its free end S² extending towards the end of the lug L. The spring S serves to make up the gap between the section B and lug L for a considerable distance.

The lug L is provided with a clamping screw S³ operating through a threaded aperture in the lug, and by tightening this screw the leaf spring is pressed against the section B which in turn is pressed against the section A, which is in turn pressed against the lug L¹. For removing or reversing and replacing the section A, it is only necessary to ease the pressure of the screw S³ and to retighten same when the sections are reassembled. To remove and reverse the other sections, the above operation is carried out as well as removal and replacement of the bolt E.

In some forms the back D may carry a depending portion D² in addition to the lug L¹ to form an added abutment for a part of the stock of section A, and such portion may be rather deeper than the stock and be cut out to provide an overhanging lip to provide a slide after the manner described with reference to the lug L¹ and lip L³.

From the foregoing description it will be readily understood that without removing the brush from its dabber foot the section A may be very rapidly changed or reversed.

What I claim is:

1. A sectional dabbing brush for woolcombing machines, comprising a back member, a plurality of brush sections removably secured on said back, one of said sections being slidable in relation to the other sections into and out of position on the back, all of said sections being individually reversible endwise with relation to each other, and flexible means for retaining said slideable section in operative position.

2. A sectional dabbing brush for woolcombing machines, comprising a back member having depending lugs at opposite side edges thereof, a plurality of endwise reversible brush sections removably secured between said lugs, one of said sections being slideable relatively to the other sections, and flexible means for clamping said slideable section between one of the other sections and one of said lugs.

3. A sectional dabbing brush for woolcombing machines, comprising a back member having depending lugs at opposite side edges thereof, a pair of endwise-reversible brush sections disposed between said lugs in abutting relation thereto and to each other, a horizontally extending bolt passing through the stocks of said brush sections and through the lugs at opposite sides of the back thereby to removably secure the brush sections on said back, an endwise reversible brush section removably disposed between one of said lugs and one of the other brush sections, and flexible means carried by one of said lugs for clamping said last brush section in abutting relation to its companion brush sections.

THOMAS LORIMER.
